UNITED STATES PATENT OFFICE.

ROBERT F. JACOBS, OF BALTIMORE, MARYLAND, ASSIGNOR OF ONE-HALF
TO CHARLES F. WALTHER, OF HOWARDVILLE, MARYLAND.

MACHINE FOR CUTTING OR SHORTENING LINOTYPE-SLUGS.

No. 823,788.

Specification of Letters Patent.

Patented June 19, 1906.

Application filed February 15, 1906. Serial No. 301,184.

To all whom it may concern:

Be it known that I, ROBERT F. JACOBS, a citizen of the United States, residing at Baltimore, in the State of Maryland, have invented certain new and useful Improvements in Machines for Cutting or Shortening Linotype-Slugs, of which the following is a specification.

This invention relates to a novel machine for cutting or shortening linotype-slugs to an exact predetermined extent in order to adapt said slugs to fit in special spaces in the type-forms of displayed advertisements.

It is the custom in displayed newspaper- advertisements where articles are described and prices therefor quoted to denote the price in figures which are much larger than the type characters comprising the descriptive matter and larger than are possible to be cast on the linotype-machine. In order to produce this style of display, it is the practice for the operator of the linotype-machine to use the matrices to compose descriptions of the articles in matrix-lines shorter than the slug which the machine is then actually casting and to finish the line or slug to its full length by using quads or spaces. The blank ends of such linotype-slugs are subsequently cut off, and when several of the short slugs are together large figures of foundry-type are inserted by hand at the shortened ends of such slugs. It is important in thus using shortened linotype-slugs and foundry-type placed at the ends of the slugs that the portion to be cut from the slugs should exactly equal the setwise space which the foundry-types require in order that the slugs and type together will be held tightly when locked up in a form. Heretofore these slugs cast for displayed advertisements have been cut by employing the ordinary machine used in printing-offices for cutting leads. This is unsatisfactory, because of the inaccuracy of measurement and because it is tedious and slow.

At the present time the standard for the scale of measurement of foundry-type is that known as the "point" system, in which seventy-two points equal one inch, and it is therefore desirable that convenient gaging means be provided and combined with a cutting-machine, whereby linotype-slugs may be cut or shortened to an exact predetermined extent according to the point system.

The object of the present invention is to

provide a slug-cutting machine with a limited number of attached but movable spacers of varying widths, the variations being according to the point system so that one or several spacers may be quickly moved into position, and thereby locate a stop or abutment where it will accurately represent a given number of points, against which may be placed one end of a linotype-slug that is to be shortened.

Referring to the drawings, Figure 1 is a perspective view of the slug-cutter machine. Fig. 2 is a view of one of the wedge-spacers. Fig. 3 shows one of the boxes in which a spacer moves and also a sliding block moved by the spacer. Fig. 4 is a longitudinal section of the machine. Fig. 5 is a cross-section of the machine. Fig. 6 is a cross-section of the platen, showing one form of spacer turned down thereon. Fig. 7 is a view of a linotype-slug, showing one end blank—that is, with no type characters—which is the style of slug the machine is intended to cut. Fig. 8 shows a block of linotype-slugs, some of which have been cut and including price-figures in larger type.

The letter A designates a bed-piece and platen resting on suitable feet a. The top of the platen has at its back a high edge or flange b. A linotype-slug c, having type characters for a portion of its length and a space near the end blank, is laid flat on the platen, with one edge against the flange b and the blank end in position to project over the end of the platen. At this end of the machine is a suitable cutter d, which may be operated by a lever e or other means to cut the blank end of the linotype-slug.

The present form of machine illustrates two styles of spacers, a wedge style and a swinging style. The spacers of this invention have varying widths and are arranged relative to each other, so as to permit any one alone to be used or any selected number to be used together in order to produce in the aggregate the desired number of points. It is to be understood that in cutting off the blank end of a linotype-slug the portion cut off should exactly equal the space which the foundry-type will require. Therefore the operator, knowing the setwise size of the figures (the foundry-type) that are to be used, which, for instance, may be thirty-four points, will put into service such spacers as in the

aggregate will amount to thirty-four points. The spacers thus put into service will locate on the platen a stop or gage against which one end of the linotype-slug will abut. This 5 will cause the blank end of the said slug to project under the cutter and beyond the end of the platen to the exact length—namely, thirty-four points—that is to be cut off.

The bed-piece at the end remote from the 10 cutter has a fixed block *f*, which serves as an abutment, and the spacers are arranged so as to be moved into an interposed position on the platen between said abutment and the cutter. This end of the bed-piece also has a 15 longitudinal open slot *g*. Some device to serve as a movable stop or gage must be employed. One form for this is shown in Figs. 1 and 4, where a slidable block *h* has one end resting upon the bed-piece. A spiral spring 20 *i* below the bed-piece or platen has one end secured to a bolt in the fixed block or abutment *f* and the other end attached to a hook *h'*, which projects down from the lower side of the slidable block *h* and through the open 25 slot *g* in the platen. This spring serves to draw the stop device *h* in a direction away from the cutter and keeps it under tension. A small knob *j* is on the slidable block and serves as a grasp part for the fingers of the 30 operator. While the end of the bed-piece nearest the cutter serves as a platen on which the linotype-slug *c* is placed to be cut, the other end has on top two parallel tongues *k*, which serve as a guideway for the stop device *h* and also for the wedge-spacers *l*, which latter will now be described.

It is to be understood the construction of the 35 spacers may be varied; but in the present instance each spacer comprises a box *N* open at one vertical side and closed at three vertical sides and at the top. Each of two opposite vertical sides of this box has a horizontal groove *k'*, which take on the tongues *k* of the guideway, and thereby enable the box to be moved or slid along the guideway. The 40 closed top of the box has a hole *m*. Within the box *N* is a wedge *l*, having a stem *m'*, which projects through the hole *m* in the box, and a spiral spring *o* surrounds the stem 45 above the box and tends to raise the wedge *l*. Thus in the present construction the wedge *l* has an up-and-down movement within the box *N*. It will be observed that each wedge *l* has two vertical parallel sides *l'* and a tapered point formed by an inclined end *l*, which bevels off between said two sides. As 50 the spring *o* normally keeps the wedge raised, a little down-pressure on the stem is required to put the wedge into service. In the present instance seven spacers are shown, but of course this number may be varied. The various widths of the spacers are denoted by the numerals 1, 2, 4, 8, 12, 18, and 24. These 55 numerals indicate one point, two points, four points, &c. In the drawings the four thinner

spacers or wedges *l* have sharp points and an undercut shoulder *p*, and the three thicker wedges have blunt points but are without shoulders.

Each spacer in the present construction 7c also comprises a slidable block *Q*, having on its two vertical parallel edges a notch or groove *k''*, which take on the tongues *k* of the guideway and enable said block to be freely moved horizontally. This block *Q* has the 75 same height and breadth of the box *N* and serves as a closure to the vertical side of the box when the particular wedge or spacer of such box is not in service. Each block *Q* also has a tenant-boss *r*, which projects into 8c or takes position into the box. The tenant-boss of each of the four thinner spaces or wedges have upward-exposed shoulders *p'*, which serve as seats or stops to receive the undercut shoulders *p* on these thinner wedges. 85 By this construction when one of the thin wedges is pressed down its undercut shoulder *p* will seat on the stop *p'* of the boss. The block *Q* of each of the thicker spacers or wedges has a tenant-boss without such seat 90 or shoulder. These bosses have an inclined or beveled face *r'* at their upper part corresponding with the inclined face of the wedge *l* and normally these inclined parts are in contact, as seen in Fig. 4. Below the inclined face *r'* the tenant-boss has a vertical wall *r''*. When the spacer or wedge is not in service, the tenant-boss is fully within the 95 box, the vertical wall *r''* of the boss being in contact with the inner wall of the said box, 100 and the spacer or wedge at such time has the raised position.

It is obvious the special slidable block *h*, used as a movable stop, may be dispensed with and instead the slidable block *Q* that is 105 nearest the cutter used as a movable stop or gage.

It will be understood that in the operation of the machine the arrangement of the parts is such that any one of the spacers alone or 110 any number of selected spacers together may be moved so as to take an interposed position on the bed or platen between the fixed abutment *f* and the cutter *d*, thereby shortening the unoccupied space on the platen adjacent 115 to the cutter, and that the linotype-slug *c* that is to be cut is placed in this unoccupied space.

The letter *s* designates a special spacer of a different form from the wedge-spacer *l*. This spacer *s* is in the form of a block fixed to 12c an arm *s'*, which is loosely pivoted on a rod *t* parallel with the platen. This spacer *s* will therefore swing upward and away from the platen and will also slide along the rod *t*. The arm of this swinging spacer has an extension *t'* beyond the pivot, whereby when the spacer is swung upward, as indicated by broken lines in Fig. 6, the said extension will turn downward and rest against the side of the platen and sustain the spacer in the up- 125 130

right position. This swinging spacer *s* is broader than either of the others and is intended to be forty-eight points. It may be used conveniently when making large cut-offs, such as half of the ordinary newspaper-column. It may be used also in combination with any of the other spacers *l*.

From this description the operation will be readily understood without further statement.

Having thus described my invention, what I claim as new, and desire to secure by Letters Patent, is—

1. A linotype-slug-cutting machine having a platen on which the slug is to lie; a cutter; and a plural number of movable spacers which are of varying width and arranged relative to each other so that any one spacer may be used alone and any number of selected spacers may be moved and used together to form a gage on the platen.

2. A linotype-slug-cutting machine having a platen on which the slug is to lie; a cutter; a stop device movable on the platen; and a plural number of spacers which are of varying width and arranged so that any one and any number may be moved to shift the stop device.

3. A linotype-slug-cutting machine having a platen on which the slug is to lie; a cutter; a movable stop device which is spring-pressed in a direction away from the said cutter; and a plural number of movable spacers which are of varying width and arranged so that any one and any number may be put into operative position.

4. A linotype-slug-cutting machine having a platen on which the slug is to lie; a cutter; a stop device movable on the platen; and a plural number of spacers all of which have a slideable movement in a direction toward and away from the said cutter and each of which

is also independently movable in another direction.

5. A linotype-slug-cutting machine having 45 a platen on which the slug is to lie; a cutter; a movable stop device which is spring-pressed in a direction away from the said cutter; and a plural number of spacers of varying width all of which are capable of 50 sliding together in the same direction, and each one of which is movable along in another direction.

6. A linotype-slug-cutting machine having a platen; a cutter having movement in a 55 plane crosswise of the platen; a fixed abutment on the platen; and a plural number of spacers any one and any number of which may be moved to take an interposed position on the platen between said abutment and 60 cutter, whereby the exact length to be cut off from the slug may be predetermined.

7. A linotype-slug-cutting machine having a platen; a cutter having movement in a plane crosswise of the platen; a fixed abutment on the platen; a gage device movable along the platen, and a plural number of spacers movable into position between the said fixed abutment and the gage device.

8. A linotype-slug-cutting machine having 70 a platen; a cutter having movement in a plane crosswise of the platen; a fixed abutment on the platen, and a plural number of wedge-spacers of varying width arranged relative to the platen so that any one of 75 which and any number of which may be moved into position.

. In testimony whereof I affix my signature in presence of two witnesses.

ROBERT F. JACOBS.
